UNITED STATES PATENT OFFICE.

GEORGE W. FRANK, OF BUFFALO, NEW YORK, ASSIGNOR TO CHARLES W. BINGEMAN, OF SAME PLACE.

DESIGN FOR A BADGE.

SPECIFICATION forming part of Design No. 30,599, dated April 25, 1899.

Application filed March 21, 1899. Serial No. 709,984. Term of patent 3½ years.

To all whom it may concern:

Be it known that I, GEORGE W. FRANK, a citizen of the United States, residing at Buffalo, in the county of Erie and State of New York, have invented and produced a new and original Design for a Badge or Similar Article, of which the following is a specification, reference being had to the accompanying drawing, forming a part thereof.

10 This design relates to the configuration of a badge or similar article, the accompanying drawing being a face view of a badge embodying my design.

15 The distinctive feature of my design consists of the figure of a dust-pan, the figure of a buffalo surmounting the dust-pan, and the representation of a pair of flags crossing one another behind the pan.

20 Referring to the drawing, A is the figure of a dust-pan, the handle α of which extends

downwardly and has the form of an incandescent-light globe.

B is the representation of a buffalo surmounting the dust-pan, and C C represent two flags, which have the appearance of crossing one another behind the dust-pan. The bottom of the dust-pan bears the representation d of the Western hemisphere.

25 The above-described representations are arranged on a background or base of circular 30 or disk form, as shown in the drawing.

What I claim is—

The design for a badge, or similar article, substantially as herein shown and described.

Witness my hand this 16th day of March, 35 1899.

GEORGE W. FRANK.
